UNITED STATES PATENT OFFICE

DAVID P. WOLHAUPTER, OF WASHINGTON, DISTRICT OF COLUMBIA, ASSIGNOR TO THE
RAIL JOINT COMPANY, OF NEW YORK, N. Y., A CORPORATION OF NEW YORK

SPLICE BAR FOR RAIL JOINTS

Application filed March 31, 1932. Serial No. 602,322.

This invention relates to improved splice bars for rail joints, and to novel methods of producing the same.

It is well known that splice bars for rail joints must fulfill various exacting requirements in order to afford prescribed factors of safety in service. Such requirements are met by the new bar of the present invention which has generally in view to provide a splice bar of exceptionally simple, inexpensive construction, inasmuch as the same may be formed from flat bar or plate stock by relatively inexpensive rolls or dies, which possess requisite strength to satisfy every requirement of safety in service, and which possess life at least equal to the life of the average splice bar of so-called standard design.

In order to provide for obtaining maximum life and most efficient and satisfactory service from a rail joint it is recognized that the joint should embody a construction not only to maintain the rails firmly connected together and in alinement, but to permit the natural wave motion of the rails to pass uninterruptedly, or substantially uninterruptedly, through the joint. Therefore, a special object of the invention is to provide a splice bar which serves to maintain the rail ends firmly connected together and supported in alined relationship, and which, at the same time, permits the natural wave motion of the rails to pass substantially uninterruptedly through the joint.

Another special object of the invention from an economical production point of view is to provide for obtaining relatively great strength and rigidity in a splice bar of relatively small mass and light weight.

With the foregoing and other objects in view, which will become more fully apparent as the nature of the invention is better understood, the same consists in the novel methods of producing splice bars, and in the novel combination and arrangements of features of the bars, as will be hereinafter more fully described, illustrated in the accompanying drawings and defined in the appended claims.

In the accompanying drawings:—

Figure 1 is a perspective view of a flat bar

of metal from which the present splice bars are formed.

Figure 2 is a similar view of the bar after it has been transversely corrugated.

Figure 3 is a similar view of the bar after it has been transversely bowed.

Figure 4 is a sectional view illustrating means for transversely corrugating the bar and simultaneously bowing the same transversely.

Figure 5 is a transverse section through a rail joint having a splice bar as illustrated in Fig. 3.

Figure 6 is a transverse section through a rail joint having a splice bar formed by a method involving an additional step over the method employed in producing a splice bar as illustrated in Figure 5.

Figs. 7 and 8 are fragmentary horizontal sectional views through a splice bar constructed in accordance with the invention and illustrating alternative forms of the corrugations thereof; and

Fig. 9 is a fragmentary perspective view illustrating an alternative embodiment of the invention.

Referring to the drawings in detail, A designates in Fig. 1 a blank from which a splice bar embodying the features of the invention is to be formed according to either of two similar but specifically different methods.

As will be observed, the blank A is in the form of a flat bar of metal of rectangular cross section and of suitable thickness and width, having straight, parallel side edges 10.

In its broader aspects the invention resides in forming a splice bar from a flat bar of metal as A either by transversely bowing the bar or by laterally bending or deflecting the side marginal portions thereof to shift the planes of the edges 10, 10 to dispose the same at such angles relative to the body of the bar as to have flat fishing engagement with the fishing surfaces of the rail. However, while this is practicable, it is preferred to additionally bend the bar A to impart increased strength and rigidity thereto. Accordingly, one suitable method of forming a splice bar from the blank A in accordance with the in-

vention consists in first corrugating the bar transversely as illustrated in Fig. 2 of the drawings, and in then bowing the bar transversely, or, equivalently, in laterally deflecting the side marginal portions thereof, as illustrated in Fig. 3, to bring the side edges 10 thereof into such angular relationship to each other as to fit, respectively, the angularly related head and base fishing surfaces 11 and 12 of a rail R as illustrated in Fig. 5. Alternatively the bar may be corrugated and bowed or, equivalently, may have its side marginal portions laterally deflected in a single operation, by being subjected to pressure between a pair of dies D, D as illustrated in Fig. 4, but, of course, the ultimate result is the same in either case, viz., strengthening of the bar and imparting rigidity thereto in the directions of both its width and its thickness by the corrugations and shifting of the flat edges 10, 10 thereof to an angular relationship corresponding to angular relationship of the fishing surfaces of the rail with which the bar is intended for use.

Regardless of whether the corrugating of the bar is effected before or simultaneously with the bowing or lateral deflection of the side marginal portions thereof, the obvious result is that different portions of the edges 10 of the bar are shifted to different planes relative to each other due to the laterally offset relationship of the adjacent inwardly and outwardly directed ribs or corrugations and to the pressure of the dies or rolls being at right angles to the plane of the blank and diagonally with respect to the laterally deflected marginal portions of the bar. In other words, the result is an undulation of each edge 10 inasmuch as each edge is higher at the middle of each inwardly directed rib of the bar than at the middle of each outwardly directed rib. This is clearly illustrated in Fig. 5 of the drawings, from which figure it is manifest that the bar, due to the undulations of its edges, has intermittent instead of continuous contact along its length with the fishing surfaces of the rail. Thus, so-called "freezing" of the bar to the rails is avoided and comparatively free running or longitudinal movement of the rails relative to the bar when the rails contract or expand is permitted. Moreover, the peculiar shape of the edges of the bar permits the rail joint to yield to allow the natural wave motion of the rails to pass substantially uninterrupted through the joint.

Referring now to Fig. 6 of the drawings, it will be observed that the bar has flat fishing contact throughout the areas of its top and bottom edges with the corresponding fishing surfaces of the rail. Flattening of the edges of the bar by removing any irregular edge portions thereof following corrugating and bowing or lateral bending of the bar may be effected in any suitable or desired manner, as

for example, by a shearing or grinding operation.

According to the embodiments of the invention illustrated in Figs. 1 to 8 the bar is transversely corrugated uniformly throughout its length and entirely across the width thereof. This, however, is not necessary, as the marginal side portions of the bar may be deflected laterally only at spaced points to leave the bar of flat cross section between said points as illustrated in Fig. 9. In this way, flat intermittent surface contact of the side edges 10' of the bar with the rail may be obtained without the necessity of cutting or grinding said edges, and at the same time substantially all of the advantages of a bar corrugated as illustrated in Figs. 1 to 8 are retained. In forming a bar as illustrated in Fig. 9 the lateral deflection of the marginal alignment of the bar preferably is effected as at 16 in vertical alignment with the bolt holes 17 and the bar between the bolt holes is permitted to remain of its original flat form as indicated at 18. Obviously, the intermittent lateral deflection of the marginal side portions of the bar may be effected at both the top and the bottom of the bar or only at the top or the bottom thereof.

Without further description it is thought that the features and advantages of the invention will be readily apparent to those skilled in the art, and it will of course be understood that changes in the form, proportion and minor details of construction may be resorted to, without departing from the spirit of the invention and scope of the appended claims.

I claim:—

1. A splice bar having vertically extending corrugations, the top and bottom portions of said bar being directed inwardly relative to the portion thereof intermediate said top and bottom portions.

2. A splice bar of uniform thickness throughout its height and length, said splice bar having vertically extending corrugations and having the top and bottom portions thereof directed inwardly relative to the portion thereof intermediate said top and bottom portions.

3. A splice bar of uniform thickness throughout its height and length, said splice bar having the top and bottom portions thereof directed inwardly relative to the portion thereof intermediate said top and bottom portions, and at least one of said inwardly directed portions being corrugated.

4. The method of forming a splice bar which consists in transversely corrugating a flat bar of metal and laterally deflecting the marginal portions of the corrugated bar relative to the portion thereof intermediate said marginal portions to dispose the edges of the bar at desired fishing angles.

5. The method of forming a splice bar

which consists in transversely corrugating a flat bar of metal and in bowing said bar transversely to dispose the edges thereof at angles corresponding to the fishing angles of rails.

5 6. The method of forming a splice bar which consists in transversely corrugating a flat bar of metal of uniform width and thickness throughout its length, and in bowing said bar transversely to dispose the edges thereof at angles corresponding to the fishing angles of rails.

10 7. The method of forming a splice bar which consists in transversely corrugating a flat bar of metal and thereafter bowing said bar transversely to dispose the edges of the bar at angles corresponding to the fishing angles of rails and to maintain all portions of each edge in a common plane.

15 8. The method of forming a splice bar which consists in transversely corrugating a flat bar of metal and simultaneously bowing said bar transversely to dispose different portions of the edges of said bar at angles corresponding to the fishing angles of rails and in different planes.

20 In testimony whereof I hereunto affix my signature.

DAVID P. WOLHAUPTER.
